John R. Nelson

UNITED STATES PATENT OFFICE.

EDGAR KIDWELL, OF MILWAUKEE, WISCONSIN, ASSIGNOR TO KIDWELL BOILER COMPANY, OF MILWAUKEE, WISCONSIN, A CORPORATION OF WISCONSIN.

BAFFLE FOR WATER-TUBE BOILERS.

Application filed October 12, 1920. Serial No. 416,394.

To all whom it may concern:

Be it known that I, EDGAR KIDWELL, a citizen of the United States, and resident of Milwaukee, in the county of Milwaukee and 5 State of Wisconsin, have invented certain new and useful Improvements in Baffles for Water-Tube Boilers, of which the following is a specification.

This invention relates to a baffle construction for boilers of the series drum and tube type wherein the water circulating path is 10 constituted by a series of transverse drums and connecting banks of water tubes, having reference especially to the baffle which is associated with the rear bank of water tubes. Owing to the limited space between the 15 curved portions of such tubes where they enter the drum, it has been customary to construct the upper part of the rear baffle 20 of a series of tiles placed edgewise one upon another, the uppermost tiles adjacent the drum being necessarily tapered or feathered to a relatively thin edge. The reduced edges of the tiles, being fragile, frequently crack 25 and the tiles, in consequence, lie unsecurely on the tubes; and hence after a short time the movement of the boiler units, because of expansion, cracks the baffle tiles, loosens the joints therebetween, and permits short 30 circuiting of the gases.

The object of my invention is to overcome the objection above-mentioned, and to that end I provide a rear baffle element comprising a lower tile portion and an upper metal 35 portion, the latter being shaped to lie in the space between the curved upper portion of adjacent tubes of the rear bank of tubes and embodying various novel features of construction which will be hereinafter described 40 and claimed.

In the drawings—

Figure 1 is a section of a part of a boiler embodying my improved baffle construction, showing the rear boiler drum and parts of 45 a bank of water tubes extending downwardly from the drum.

Fig. 2 is a section, on a larger scale, of the baffle section and its connections.

Referring to the drawings, 5 designates a 50 rear steam-and-water drum; 6 designates a rear bank of water tubes having curved upper ends entering the wall of the drum, and 7 a bank of tubes leading to said drum from

a forward drum (not shown). 8 designates one of the longitudinal girders which support the drum 5, and 9 designates a lower transverse girder which supports the body of the tile baffle 10 between two adjacent rows (11) of the rear bank of tubes. The girders 8, 9 are supported in the boiler setting as usual.

As illustrated in the drawings the curved upper portions of the two rows of tubes between which the rear baffle is arranged converge as they approach and enter the drum, 65 thus affording but limited space adjacent the drum for the reception of the upper end of the baffle. According to my invention, I terminate the body of the tile baffle 10 below the girder 8, and provide a separate unit 70 or section for the upper part of the baffle. This section, in its preferred form, comprises a metal plate 12 appropriately shaped to lie between adjacent rows of tubes, its lower portion being bolted or otherwise secured to a basal bar 13 preferably of channel iron. This bar is disposed below the girder 8 and is adjustably secured thereto, preferably by means of bolts 14 passing through the lower flanges of the girder, so 75 that by proper manipulation of the bolts the metal section 12 can be vertically shifted in a manner to force its upper edge into 80 close contact with the wall of the drum, thus securing the parts in close relation to each 85 other.

The lower end of the plate 12 depends below the bar 13, thus providing an angular portion which receives the top of the uppermost tile of the baffle portion 10, which portion is built up on the girder 9 as usual. The joint between the contiguous baffle tile and the angular lower portion of the upper metal section can be cemented, if desired, after the 90 construction has been installed in the boiler 95 structure.

Adjacent the upper end of the rear side of the metal section is secured an angle iron 15 which provides a seat for asbestos packing, as 16, which packing can thus by the 100 described mode of adjusting the baffle section be crowded against the wall of the drum in order to ensure a tight joint under all conditions of service.

It is to be understood that I do not limit 105 my invention to the details of construction

2
herein disclosed, as the same may be modified within the principle of my invention and the scope of the appended claims.

I claim—

- 5 1. In a boiler of the series drum and tube type, the combination with a rearward drum and a rearward bank of water tubes extending therefrom, of a baffle element associated with said tubes, said element comprising a tile structure spaced below the drum and a metal member occupying the space between said structure and the drum and shaped to lie in the upper curved space between adjacent rows of tubes, a rigid support below 10 the drum, and a connection between said support and the plate member for vertically adjusting said member to force its upper edge into close contact with the opposing wall of the drum.
- 15 2. In a boiler of the series drum and tube type, the combination with a rearward drum and a rearward bank of water tubes extending therefrom, of a baffle element associated with said tubes, said element comprising a tile structure spaced below the drum and a metal member occupying the space between 20 said structure and the drum and shaped to lie in the upper curved space between adjacent rows of tubes, a rigid support below 25 the drum, and a connection between said support and the plate member for vertically adjusting said member to force its upper edge into close contact with the opposing wall of the drum.
- 30 20 2. In a boiler of the series drum and tube type, the combination with a rearward drum and a rearward bank of water tubes extending therefrom, of a baffle element associated with said tubes, said element comprising a tile structure spaced below the drum and a metal member occupying the space between 35 said structure and the drum and shaped to lie in the upper curved space between adjacent rows of tubes, a basal bar fast on said 40 plate above the lower edge of the latter, to provide an angular seat to receive the upper 45 part of the tile structure, and an adjustable connection between the said bar and the girder.

the drum, and a connection between said support and the plate member for vertically adjusting said member to force its upper edge into close contact with the opposing wall of the drum, and means on said member, adjacent its upper edge, to receive and support packing against the wall of the drum.

3. In a boiler of the series drum and tube type, the combination with a rearward drum, a rearward bank of water tubes extending therefrom, and a supporting girder, of a baffle element associated with said tubes, said element comprising a lower tile structure terminating below the girder, and an upper metal structure occupying the space between the tile structure and the drum, said metal structure comprising a plate shaped to lie in the upper curved space between adjacent rows of tubes, a basal bar fast on said plate above the lower edge of the latter, to provide an angular seat to receive the upper part of the tile structure, and an adjustable connection between the said bar and the girder.

Signed at Milwaukee, in the county of Milwaukee and State of Wisconsin, this 8th day of October A. D. 1920.

EDGAR KIDWELL.
